CLAIM

The ornamental design for a tape measure with laser distance measurer, as shown and described.

DESCRIPTION

FIG. 1 is a front, right-side perspective view of the tape measure with laser distance measurer according to an embodiment of the present claimed design.

FIG. 2 is a right-side view according to an embodiment of the claimed design.

FIG. 3 is a left-side view according to an embodiment of the claimed design.

FIG. 4 is a front view according to an embodiment of the claimed design.

FIG. 5 is a rear view according to an embodiment of the claimed design.

FIG. 6 is a top view according to an embodiment of the claimed design.

FIG. 7 is a bottom view according to an embodiment of the claimed design; and,

FIG. 8 is a rear, left-side perspective view of an embodiment of the claimed design.
